Patented Jan. 12, 1960

187,039

CANISTER OR THE LIKE

George J. Strauss, Los Angeles, Calif.

Application June 23, 1959, Serial No. 56,490

Term of patent 14 years

(Cl. D44—6)

FIG. 1.

FIG. 2.

Fig. 1 is an isometric view showing a canister or the like embodying my new design;

Fig. 2 is a side elevational view of the same.

The sides not shown are plain.

I claim:

The ornamental design for a canister or the like, substantially as shown and described.
